COMBINATION POURING SPOUT AND
SIFTER

Arthur Read, Portland, Oreg.

Application April 5, 1941, Serial No. 387,035

2 Claims. (Cl. 209—370)

This invention relates to improvements in a combination pouring spout and sifter adapted to be either permanently or removably attached to cartons containing cake flour and the like.

One of the principal objects of the invention is the provision of an article of this character which may be quickly and conveniently attached to a carton either during the manufacturing of the carton, during the filling operation, or applied by the user after purchasing a filled carton.

A further object is the provision of a closure plate hinged to the forward end of the article to close the aperture in the carton, and so formed that when moved into an open position, it provides a pouring spout.

The foregoing and other objects will appear as my invention is more fully hereinafter described in the following specification illustrated in the accompanying drawing and finally pointed out in the appended claims.

In the drawing:

Figure 1 is a perspective view of a carton showing the device applied to one wall thereof and with the pouring spout in a closed position to form a seal.

Figure 2 is a slightly enlarged, fragmentary view of Figure 1 showing the pouring spout in open position.

Figure 3 is a perspective view of the combination sifter and pouring spout in the form adapted to be applied to the carton during its manufacture.

Figure 4 is a top plan view of the device shown applied to a carton.

Figure 5 is a perspective view of a modified form of the invention wherein the bottom and side walls of the device are formed with cutting edges enabling it to be thrust through the wall of a filled carton to cut its own aperture.

Referring now more particularly to the drawing:

In Figure 3, reference numeral 1 indicates the main body of the device comprising a flat bottom wall 2 and rearwardly tapering angular side walls, 3 and 4. The top surface of the device is formed with a rim or flange 5 to which is attached by any suitable means, such as, solder or the like, a screen 6 to serve as a sifter.

Pivottally mounted, as at 7, to the flange at the inner end of the device is an agitator, generally indicated at 8, and consisting of a triangular-shaped framework formed with ribs 9 diverging from and preferably made integral with a plate 10 which is held in sliding contact with the flange 11 at the open end of the device by a

portion 12 punched out of the flange 11. The forward end of the plate 10 is provided with an actuating handle 13 by means of a hinge 14, which normally allows the handle to be suspended from the plate 10 in a vertical position, as shown, so as not to interfere with the closing operation of the pouring spout. The rearward end of the frame 8 is formed with vertical projections 15 to further agitate the contents of the carton upon swinging the agitator about its pivot point 1. To the forward end of the bottom wall 2, I attach, by any approved type of hinge, a pouring spout comprising a bottom wall 16 and two integral side walls 17, whose upper rear ends are formed with projections 18 adapted to bear against the inner surface of the wall of the carton, and to serve as limit stops when moving the spout into an open position. The spout is attached to the floor 2 by any suitable type of hinge, as aforesaid, located along the line 19, if the device and pouring spout are made of metal. If, however, the bottom and side walls of the sifter and pouring spout are made of cardboard, or the like, then a hinge may be formed by a fold-line located, as at 19.

In the form of the invention illustrated in Figure 5, the body of the sifter, as well as the pouring spout, is made of metal; and the upper edges of the side walls are formed with cutting edges 20. The bottom wall 21 is preferably pointed, as at 22 and also sharpened so that the device may readily cut its own aperture through the wall of the carton to which it is to be applied. The forward ends of the frame for the sifter terminate in a frame 23, formed with an integral projection 24 tilted upwardly, and preferably rolled back on itself, as at 25, to provide a cam or lifting surface for the punched-out flap of the carton formed by the cutting walls. In this form of the invention, the sifter, the agitator, and its handle are identical with those shown and described in connection with Figure 3. The pouring spout is attached to the frame 23 by a hinge 26. This form of the invention may be conveniently thrust through the wall of the carton and moved inwardly to a position where the frame 23 bears firmly against the outer surface of the wall of the carton. To make the attachment more permanent, an adhesive may be applied to the inner surface of the frame for causing it to adhere to the wall of the carton. One of the features of the frame is that it provides reinforcement for that portion of the carton wall in which the aperture has been formed.

While I have shown a particular form of em-

bodiment of my invention, I am aware that many minor changes therein will readily suggest themselves to others skilled in the art without departing from the spirit and scope of the invention. Having thus described my invention, what I claim as new and desire to protect by Letters Patent is:

1. A combination sifter and pouring spout comprising a hollow body member having tapered side walls formed along their upper edges into cutting edges and a bottom wall formed with a forwardly extending cutting edge, a sifter mounted across the side walls, an agitator swingably mounted with respect to the sifter and provided with a hingedly mounted handle, a pouring spout hinged to the forward end of the body member and adapted when in a closed position to seal

the aperture formed in the carton for the insertion of the body member.

2. A combination sifter and pouring spout for cartons, comprising a hollow body member having a bottom wall and two rearwardly tapering side walls, a pouring spout hingedly mounted to the forward end of the bottom wall, a sifter of flat formation mounted upon said side walls, an agitator swingably mounted above the sifter and 10 in wiping contact therewith, said body member being of greater width than the pouring spout, whereby the front edges of the body member will bear against the marginal edges of an opening in the carton through which the pouring spout may be swung to an open or closed position with respect thereto.

ARTHUR READ.
